William O. Lee

UNITED STATES PATENT OFFICE.

WILLIAM O. LEE, OF DETROIT, MICHIGAN.

WRENCH.

SPECIFICATION forming part of Letters Patent No. 450,516, dated April 14, 1891.

Application filed November 20, 1890. Serial No. 372,018. (No model.)

To all whom it may concern:

Be it known that I, WILLIAM O. LEE, a citizen of the United States of America, residing at Detroit, in the county of Wayne and State of Michigan, have invented certain new and useful Improvements in Wrenches, of which the following is a specification, reference being had therein to the accompanying drawings.

10 This invention pertains to a new and improved wrench, having for its object the production of simple and highly efficient means for securing the reversible stationary jaw, and also means for readily and easily effecting the adjustment of the movable or sliding jaw.

The invention comprises in a combined nut and pipe wrench a shank having a rigid reversible jaw, an end cap and screw for holding said jaw, and a sliding adjustable jaw having a screw and a slide for disengaging said screw from contact with said shank, substantially as hereinafter fully set forth, and particularly pointed out in the claims.

25 In the accompanying drawings, Figure 1 is a side elevation of my improved wrench. Fig. 2 is a longitudinal sectional view thereof. Fig. 3 is a view of the parts of the movable jaw detached. Fig. 4 is a horizontal sectional view of the end of the shank, taken through the reversible jaw.

Referring to the drawings, A designates the shank, and a the handle, the same being preferably made of one piece of hollow metal. 35 In the upper surface of this shank is formed a disconnected or segmental screw-thread a', and the outer end of this shank is formed into a projection or extension a², having at its inner end tapered or inclined sides a³, ending at the sides of the shank.

B is the stationary reversible jaw, having a central opening b, the side walls of which are V-shaped, their vertexes being at central opposite points. The inner opposite taper of the sides of this opening is designed to correspond with the tapering sides of the extension of shank A, upon which the jaw is firmly held by an end cap C, provided with inwardly-projecting wings b' b', the outer sides of which taper so as to fit flush against the corresponding tapering sides of the open-

ing B. These wings hug the extreme end of the extension a², and the cap C is firmly held in place by a screw D, passed therethrough and working in a threaded aperture in the 5 end of the shank, said screw having a milled head d to permit of its ready manipulation. One face of this jaw is curved and provided with a series of transverse teeth d', which are used when the wrench is employed for 60 turning pipes, rods, or bolts. In the other end of this jaw are formed two V-shaped grooves or recesses d², by means of which the wrench is always applicable for turning nuts. The reversal of the jaw B is readily effected 65 by first removing the screw D and cap C, which are replaced when the jaw is again inserted on the end of the shank, the arrangement of the tapered end of the shank, the opening of the jaw B, and the wings of the 70 removable cap being such that said jaw is firmly held in place in both positions.

E is the sliding adjustable jaw having an opening through which the shank is extended, and its rear portion is preferably made in skeleton form and is provided with two upwardly-projecting hollow extensions e e', having circular grooves or recesses e².

F is the rotating screw projecting through an upper opening f of the jaw, and its thread 80 is designed to engage the screw-thread a' of shank A. The screw F is provided at its ends with beveled or inclined extensions f' f² of cone shape, which are designed to be located in and inclosed by the hollow extensions e e' 85 of the jaw. Upon the reduced ends f³ of these beveled extensions are designed to bear yokes or saddles f⁴ of approximately U shape, said yokes or saddles being held to their place by spiral springs f⁵ encircling studs or short 90 extensions f⁶ of said yokes located in the grooves or recesses e². These springs and yokes hold the screw F normally in engagement with the thread of the wrench-shank, and by turning the exposed portion of said 95 screw a slow adjustment of the jaw E can be secured.

G is a slide for bodily disengaging the screw F from contact with shank A, whereby a quick adjustment of the jaw E can be had. 100 This slide consists of an oblong frame g, having inwardly-tapering side bars g', connect-

ing end bars g^2 , and a projected end g^3 , having a thumb-piece g^4 bent at right angles and parallel with the end of jaw E.

Upon the end bars g^2 are formed inclined 5 or tapered lugs g^5 g^6 , designed to engage the beveled or inclined extensions of the screw F. In their normal position the reduced ends of the screw rest upon these lugs, one of which g^6 is provided with a groove or recess g^7 for 10 the end of the extension f^2 , the taper of the other extension f^3 conforming to that of lug g^5 . By pushing inwardly on the slide G the tapered lugs thereof will by contact with the beveled extensions of the screw force the latter 15 outward from contact with the shank as against the action of the spring-pressed yokes or saddles, the screw being permitted to so move by reason of two slots g^8 in the hollow extensions e e' through which the beveled 20 portions extend. As soon as pressure is removed from the slide the springs will force the screw into contact with the wrench-shank and cause the rearward movement of the slide. Thus it will be seen that a slow movement 25 of the adjustable jaw can be secured by turning the screw with the thumb or finger and that a rapid or quick adjustment is obtained by the slide, which disengages the screw from the thread on the shank and permits the easy 30 manipulation of said jaw.

The advantages of my invention will be apparent to those skilled in the art to which it appertains, and it will be particularly observed that the same comprises a combined nut and 35 pipe wrench capable of being easily transposed, and that the sliding jaw is readily and quickly adjusted and can be firmly held at any point. The invention is also extremely simple, inexpensive, and free from complication.

I claim as my invention—

1. In a wrench, the combination, with the shank having a tapering end and the adjustable jaw, of the rigid reversible jaw provided 45 with an opening the walls of which are V-shaped or divergent, and the securing end cap having wings conforming to said walls, where-

by said jaw is rigidly secured on said shank and is rendered reversible, substantially as set forth.

2. In a wrench, the combination, with the shank having an extension provided with tapering sides and the adjustable jaw, of the rigid reversible jaw having an opening and opposite V-shaped or divergent side walls, the end cap provided with tapering wings hugging the sides of said extension and fitting the outer ends of said V-shaped or divergent walls, and the screw for securing said cap in place, engaging a threaded aperture of said shank, substantially as set forth.

3. In a wrench, the combination, with the shank having a screw-thread, of the sliding adjustable jaw herein described, the screw located in said jaw and engaging said screw-thread, the springs bearing on said screw, and the slide for raising said screw at both ends, whereby the same is disengaged from said screw-thread, substantially as set forth.

4. In a wrench, the combination, with the shank having a screw-thread, of the sliding adjustable jaw herein described, the screw located in said jaw and engaging said screw-thread and having beveled or inclined extensions at its ends, and the slide having inclined lugs engaging said extensions, substantially as set forth.

5. In a wrench, the combination, with the shank having a screw-thread, of the sliding adjustable jaw herein described, having hollow extensions and opposite slots, the screw located in said jaw and having beveled or inclined extensions and reduced ends, the spring-pressed yokes or saddles engaging said reduced ends and located in said hollow extensions, and the slide having inclined lugs engaging said extensions and provided with a thumb-piece, substantially as set forth.

In testimony whereof I affix my signature in presence of two witnesses.

WILLIAM O. LEE.
